COMBINED FOOD STIRRING PADDLE AND SCRAPER

Joseph A. Larson, Sparta, Wis., assignor to Sparta Brush Co., Incorporated, Sparta, Wis., a corporation of Wisconsin

Filed Aug. 7, 1963, Ser. No. 76,141

Term of patent 14 years

(Cl. D44—29)

FIG. 1 is a perspective view of a combined food stirring paddle and scraper showing my new design;

FIG. 2 is a fragmentary rear elevational view of the lower portion thereof, on an enlarged scale;

FIG. 3 is a fragmentary side elevational view on an enlarged scale, with intermediate portions broken away for convenience of illustration;

FIG. 4 is a sectional view on an enlarged scale, taken on line 4—4 of FIG. 1; and

FIG. 5 is a sectional view on an enlarged scale, taken on line 5—5 of FIG. 1.

I claim:

The ornamental design for a combined food stirring paddle and scraper, as shown and described.
